[57] CLAIM

The ornamental design for a postcard, as shown and described.

DESCRIPTION

FIG. 1 is a front elevational view of a postcard, showing my new design. The broken lines indicate perforations of the card stock whereat the cutout can be separated from the remainder of the postcard;

FIG. 2 is a top plan view thereof, the bottom plan view being a mirror image thereof;

FIG. 3 is a right side elevational view thereof, the left side being a mirror image thereof; and

FIG. 4 is a rear elevational view thereof.
